FINGER ACTUABLE THROTTLE LEVER FOR LIGHTWEIGHT VEHICLES

Guy-Noel Chaumont, 138 Gaulin St.,
Princeville, Quebec, Canada

Filed May 23, 1969, Ser. No. 17,308

Term of patent 14 years

Int. Cl. D8—03

U.S. Cl. D8—161

FIG. 1

FIG. 2

FIG. 3

FIG. 4

FIG. 1 is a top plan view of a finger actuable throttle lever for light-weight vehicles showing my new design;

FIG. 2 is a side elevational view thereof;

FIG. 3 is a plan view as seen from underneath FIG. 2;
FIG. 4 is an elevational view as seen from the left of FIG. 2; and

FIG. 5 is an elevation view as seen from the right of FIG. 2.

I claim:

The ornamental design for a finger actuable throttle lever for lightweight vehicles, as shown.
